[57] CLAIM

The ornamental design for a container lid, as shown and described.

DESCRIPTION

FIG. 1 is a perspective view of a container lid showing my new design on a container shown in phantom;

FIG. 2 is a top plan view thereof;

FIG. 3 is a front elevational view thereof;

FIG. 4 is a rear elevational view thereof;

FIG. 5 is a bottom plan view thereof;

FIG. 6 is a side elevational view thereof; and,

FIG. 7 is a side elevational view thereof opposite that shown in FIG. 6.

The broken line showing is for illustrative purposes only and forms no part of the claimed design.
